[57] ABSTRACT

There is disclosed a diode-resistor addressing apparatus and method wherein, with respect to at least one of the conductor arrays on such panel, the diode-resistor addressing array is used for supplying sustaining potential to the panel in addition to coacting with potentials on the crossing conductor arrays for addressing purposes. Although the invention is applicable to both row and column arrays, it is especially suitable for providing the two level signal voltages for the column or "Y" conductors in such panels.

**DIODE-RESISTOR ADDRESSING APPARATUS
AND METHOD FOR GASEOUS DISCHARGE
PANELS**

The present invention is directed to method and apparatus for supplying operating voltage to cross conductor matrices of gaseous discharge display panels. Such panels are disclosed in detail in Baker, et al., U.S. Pat. No. 3,499,167 and Bitzer, et al., U.S. Pat. 3,559,199. In the Baker, et al., patent, such a panel is constituted by a pair of glass plate members joined in spaced apart relation by spacer sealant member. Each glass plate member carries a dielectrically coated multiple conductor array, the row and column conductors typically being orthogonally related with the crossing points of the conductors in such matrix being addressable by application of operating voltages to the respective conductors in such arrays locating the cross points. Such operating voltages are constituted by address pulse voltages and sustainer voltages and, typically, in such systems, the sustainer voltage is applied one-half to the row conductors and one-half to the column conductors.

The significant part of the circuit cost for operating such display panels is the cost of circuitry associated with each individual conductor or electrode on the panel. It is possible to provide for operating such panels with only a single diode and a single resistor for each panel conductor. Though the circuit principles being considered in accordance with the present invention can be applied to both axes, it is especially suitable for providing the two level signals for the Y or column electrodes on such panels. According to the invention, the sustainer voltage on the Y or column electrode arrays of the panel are adjusted in coincidence with the application of write and erase voltage pulses to the opposite electrode array in the panel.

The above and other objects, advantages and features of the invention will become more apparent from the following specification when taken in conjunction with the accompanying drawings wherein:

FIG. 1A is a diagrammatic block diagram of a gaseous discharge display panel and system for supplying operating potentials thereto incorporating the invention; and

FIGS. 1B and 1C show waveform diagrams of the voltages applied to the X electrode and Y electrodes, respectively; FIG. 2 is a partial circuit diagram showing the diode-resistor array for supplying the operating potential shown in FIG. 1C to the Y panel electrode;

FIG. 3 is a waveform diagram of the X and Y sustain sources shown in accordance with a feature of the invention; and

FIGS. 4 (A and B) shows the partial schematic diagram (FIG. 4B incorporating a portion of FIG. 2) with the driving input of the diode groups and resistor groups incorporating the invention.

Referring now to FIG. 1 of the drawings, a gaseous discharge display panel 10, preferably of the type shown in Baker et al Pat. No. 3,499,167, is constituted by a pair of support plates 11 and 12 each carrying a separate conductor array 13 and 14, respectively. The conductor array 13 is designated the Y electrode or column conductor array and the conductor array 14 being designated the row or X conductor array.

The row or X electrode array 14 is driven from a resistor-diode selection matrix 16 which may be conventional and receives its input control and data or infor-

mation signals from data and control circuit 20. It will be noted that resistor-diode selection circuit 16 is electrically floated upon an X electrode sustainer supply 21 which is also controlled by signals from data and control 20. The Y electrode array 13 is supplied with discharge condition manipulating and sustaining voltage from a diode-resistor array 17 which is shown in greater detail in FIG. 2. The sustainer voltage supply 22 for the column or Y electrode array, in accordance with the invention, is modified by the diode-resistor array in a manner shown in FIG. 1C. It will be appreciated that the showing of V_{sy} separate from the diode-resistor array 17 is for purposes of illustration.

As indicated earlier, the X electrode signal with write and erase pulses shown in FIG. 1B is operated in the normal addressing fashion with the write pulse shown in FIG. 1B being a pulse voltage algebraically added to the square wave sustainer voltage and, the erase pulse is essentially a narrow erase pulse which is likewise algebraically added to the sustainer voltage on the X electrode system, it being illustrated in its normal time position relative to the sustainer signal voltage on the X electrodes. Thus, the erase pulse is a narrow pulse applied between the pull down and pull up versions of the sustainer signal on the X electrode.

As shown in FIG. 1C, when the sustaining signal is least positive, a low impedance is provided for driving the panel electrodes by having the least positive sustainer signal so that the diodes D_1 and D_2 shown in FIG. 2 are forward biased. That is, if the diode current is greater than the panel discharge current and the panel charging current (the panel is essentially a capacitive load), then the electrode voltage is clamped at essentially zero volts. When the sustaining signal level is most positive, the impedance driving the electrodes is low for only one direction of current flow. This is normally sufficient, but if for a special situation, a low impedance were required for both directions of current flow, the bias technique for the least positive sustainer can also be used for the more positive level. A biased technique for least positive sustainer levels is shown in FIG. 1C and is the addressing scheme illustrated in FIG. 2. The panel output to the panel electrode is connected to the node point between the resistor R and diode D_2 for each addressing point. The diodes D_1 provide a return path to the sustainer supply. Thus, with respect to the circuit shown in FIG. 2 (and also in FIGS. 4A and 4B), the sustainer voltage applied to the panel Y electrodes is also used during address times to the X electrodes in the panel.

When it is desired to write at a selected cross point on the panel, assuming that it is desired to write at panel Y electrode 44, the conductor 45 is not driven by the up sustainer input so that the voltage on the down sustainer input 46 pulses the resistor R 44 so that the voltage at the nodal point connected to the panel supplies the "selected write signal" (the dotted line shown in FIG. 1C below the words "selected write") to the selected Y electrodes of the panel. In the event it is desired not to write at the selected crossing point of panel Y conductor 44 with any X electrode crossing, the portion of the signal labelled "selected write" is not generated, e.g., prevented, by the diode-resistor matrix 17.

Power is dissipated in the resistors according to the bias current required to maintain the desired low impedance. The power required for this purpose may be re-

duced by having bias current available only when required, as indicated by the signal levels in FIG. 3. As shown in FIG. 3, to reduce power it is important that the sustainer bias level b of the Y sustainer source encompass the sustainer transition st and panel discharge current of the X sustainer source.

The diode-resistor array of FIG. 2 is shown with driving inputs to the diode groups and resistor groups in FIG. 4. Note that in accordance with the invention both diode driving signals and resistor driving signals, which are normally used for addressing, are also used to supply sustaining signals.

The transistor driven diode matrix of FIG. 4A may be used to control the diode-resistor matrix of FIG. 4B. Each vertical select transistor VQ and each horizontal select transistor HQ are supplied with on-off control signals in accordance with a code permutation to control gate diodes D₃ and D₄, respectively at each diode matrix intersection. Each such diode matrix intersection of FIG. 4A is connected to a horizontal selection line in the diode-resistor matrix to thereby bias each diode D₂ at selected times and for selectable time intervals to constitute the up sustainer input. The resistors R in the diode-resistor matrix are pulsed by transistors RP which constitutes the down sustainer inputs.

While a preferred embodiment of the invention has been shown and described herein, other obvious embodiments are possible.

What is claimed is:

1. In a system for supplying operating voltages, constituted by selectively applied write and erase pulse voltages and a square wave sustaining voltage, to sites in a gas discharge panel row-column conductor arrays, including a first selection matrix for selecting row conductors and a second selection matrix for selecting column conductors, each said selection matrix including a plurality of gate elements, connected in a multiplex array, each gate element having a common nodal point connected to an individual conductor in one of said arrays, and through which nodal point said operating voltages are applied to each individual conductor, one half cycle of said conductor arrays and the other half cycle of said sustaining voltage being applied to the other of said conductor arrays, the improvement comprising means for controlling at least one of said selec-

45

tion matrices to supply the one half cycle of said square wave sustaining voltage to the conductor array supplied thereby and further control means for controlling the half cycle of sustaining voltage applied to said other conductor array, in cooperation with said write and erase pulse voltages applied to the opposite conductor array connected to the other of said selection matrices to manipulate the discharge condition of selected sites in said panel.

2. The invention defined in claim 1 including first means connected to said at least one selection matrix to apply an up sustainer control signal thereto to cause an increase in potential at all nodal points in said at least one selection matrix and second means connected to said at least one selection matrix to apply a down sustainer control signal thereto to cause a decrease in potential at all said nodal points to thereby produce said square wave sustainer voltage.

3. The invention defined in claim 2 wherein said first means includes a diode matrix constituted by a plurality of diode gate pairs, with intermediate points between said pairs being connected to supply said up sustainer signal.

4. The invention defined in claim 3 wherein said second means includes a plurality of transistor switch means each individually controllable and connected to said at least one selection matrix to provide said down sustainer control signal.

5. The invention defined in claim 1 wherein said control means includes a diode matrix having horizontal and vertical selection conductors, a pair of diodes constituting gates at each intersection thereof, means connected to said horizontal and vertical selection conductors for supplying permuted signals thereto for controlling the conduction and non-conduction conditions of said pair of diodes, and means connecting an intermediate point on each said diodes to said at least one selection matrix to control same thereby.

6. The invention defined in claim 1 wherein each said gate element is constituted by a single resistor and a single diode for each panel electrode.

7. The invention defined in claim 1 wherein one conductor axis has a sustainer bias which encompasses the sustainer transition for the opposite electrode axis.
